Oct. 2207

Jacob Steffe, of Philadelphia, Penna.
Letters Patent No. 2207-Dated Oct. 14-1865,
Design for a Stove.

The schedule referred to in these Letters Patent and making part of the same.

Scall when it may concern;

Bes't known to that Jacob Steffe, of the
City of Philadelphia in the State of Pennsylvania, have in-
vented or produced a new and original design for a Stove of
which the following is a full, clear and exact description,
reference being had to the accompanying drawing, making
a part of this specification, and to the letters of reference
marked thereon.

For convenience of reference this design may
be divided into four parts viz; the base A, fuel holder B
body C, and cap D, all of which are of cast iron.

The base consists of the flat or horizontal por-
tion A, and the curved raised portion A', with which the
fuel holder B connects, the said two portions being or-
namented as shown in the drawing.

The fuel holder is curved and fluted ver-
tically as shown at b, b', and is surrounded at its mid-
dle by the ornamental flange b², as shown.

The body is cylindrical and is provided with
a slot c, both of which are ornamented with raised
figures, as shown.

The cap is made to project over the body C, is
shaped and ornamented as shown, and also surmounted
by the ornament of open work d, as shown.

What I claim as my invention and desire to
secure by Letters Patent is

The design for a stove herein set forth.

Witnesses;
